UNITED STATES PATENT OFFICE.

JAMES C. GARNER, OF HOUSTON, TEXAS, ASSIGNOR, BY MESNE ASSIGNMENTS, TO THE GARNER GIN COMPANY, INC., OF HOUSTON, TEXAS, A CORPORATION OF TEXAS.

PNEUMATIC ROLLER GIN.

1,406,634.

Specification of Letters Patent. Patented Feb. 14, 1922.

Application filed March 17, 1919, Serial No. 283,204. Renewed July 5, 1921. Serial No. 482,559.

To all whom it may concern:

Be it known that JAMES C. GARNER, a citizen of the United States, residing at Houston, in the county of Harris and State 5 of Texas, has invented certain new and useful Improvements in a Pneumatic Roller Gin, of which the following is a specification.

This invention relates to new and useful 10 improvements in a pneumatic roller gin.

One object of the invention is to provide a device of the character described, which is particularly designed for the purpose of ginning cotton.

15 Another object of the invention resides in the provision of a device of the character described, which includes a fixed stripper blade and a rotatable drum co-acting therewith, said drum being arranged to carry 20 the seed cotton into contact with said blade whereby the lint is stripped from the seed; all in combination with a reciprocating stripper bar, which operates against the cotton and assists in the stripping operation 25 and prevents the congestion of the cotton and seed against the blade.

A further feature of the invention resides 30 in the provision of reciprocating fingers which hold the cotton against the drum, and at the same time impart a reciprocating movement thereto, thereby preventing congestion and assisting in stripping the lint from the seed.

A still further feature of the invention 35 resides in the provision of means for pneumatically feeding the seed cotton to the gin and carrying the ginned cotton therefrom for delivery to the condenser.

With the above and other objects in view, 40 the invention has particular relation to certain novel features of construction, operation and arrangement of parts, an example of which is given in this specification and illustrated in the accompanying drawings,

45 wherein:

Figure 1, is a front elevation of the gin.

Figure 2, is a rear view thereof, shown partially in section.

Figure 3, is a vertical sectional view taken 50 on the line 3—3 of Figure 1.

Figure 4, is a vertical sectional view taken on the line 4—4 of Figure 2.

Figure 5, is an end view of the device.

Figure 6, is a fragmentary sectional view.

Figure 7, is a sectional view of a form of connection employed.

Figure 8, shows an enlarged fragmentary sectional view of the drum and co-acting blade, showing the stripper bar in elevated position.

Figure 9, is a similar view showing the stripper bar in lowered position, and

Figure 10, shows a plan view of the reciprocating finger bar and the means for operating the same.

Referring now more particularly to the drawings, wherein like numerals of reference designate similar parts in each of the figures, the numeral 1, refers to a supporting frame work having the aligned bearings 2, 3 and 4, wherein the hollow shaft 5 rotates. Between the bearings 2 and 3, this shaft is enlarged forming the drum 6, which is perforated to permit the free inlet of air. Fixed on one end of the shaft 5 between the bearings 3 and 4, is the pulley 7, through which the shaft and drum are rotated.

Supported by the framework, behind the drum, is the transverse flue pipe 8, through which an air current is induced by means of a suitable current generator, (not shown) and the ends of the hollow shaft 5 are connected with the pipe 8, through the branch pipes 9, 9, whose rear ends are tapped into the flue pipe 8, and whose other ends are connected to the respective ends of the shaft 5, by means of the connections 10, 10.

The gin is provided with a hopper 11, through which the seed cotton may be fed to the drum 6, and said drum, rotating in the direction indicated by the arrow in Figure 6, carries the cotton against the fixed transverse stripper blade 12. This blade is fixed to the support 13, in front of, and beneath, the drum 6, and said blade is arranged tangential with respect to the drum, its upper edge being beveled, at 14, to conform to the contour of the drum, and to form a stripping edge 14', extending from end to end of the drum and arranged closely adjacent thereto. A vertically movable stripper bar 15 rests against the front side of the blade 12, and is provided at its ends with clamps 16, 16, through which it is fastened to the lift arms 17, 17. The lower ends of the arms 17 are attached to coil springs 18, 18, secured to adjustable brackets carried by the framework and the upper ends there-

of are adjustably attached to the respective cam levers 19, 19, by means of adjusting bolts 20, 20, which pass through the respective slots 21, 21, in said levers, and are tapped into said arms. The forward ends of the levers 19, 19, are hinged to the respective blocks 21', 21', which are seated in the grooves 22, 22, of the framework, and are secured therein by means of the bolts 23, 23. 5 The lower ends of these bolts have the heads 24, 24, and they pass upwardly through the oblong slots 25, 25, and through the blocks 21, 21, and their upper ends receive the nuts 26, 26. The blocks 21 are adjustable toward and 10 from the drum 6, but are held in fixed position by the front and rear set screws 27, 27, and 28, 28. It is obvious that said blocks may be adjusted in the grooves wherein they are seated by loosening the nuts 26, and by then 15 suitably adjusting the set screws 27 and 28, and thereby the stripper bar 15 may be adjusted for the purpose hereinafter set forth. The free ends of the cam levers have anti-friction bearings, which ride upon the 20 eccentrics 29, 29, carried by the shaft 5, just inside of the bearings 2 and 3, and said levers are alternately lifted by said eccentrics, and lowered by said pull springs 18, so as to reciprocate the stripper bar 15, up 25 and down, through the arms 17, 17.

The drum 6 is rotated rapidly and carries the seed cotton against the edge 15 of the blade 12. The suction through the perforations of the exposed front of the drum holds 30 the seed cotton closely against the front part of the drum and the seed are arrested by the blade and the lint is pulled by the rapidly rotating drum, from the seed, held by the blade, the lint passing on around the drum between it and the blade. Slidably mounted in suitable bearings carried by the front part of the framework is a reciprocating cross bar 37, which carries the spaced 35 fingers 38, which are arranged in front of the drum and decline toward the same. This bar has a beveled roller 39, which projects into the cam shaped groove 40, of the short transverse shaft 41. This shaft is rotatably mounted in suitable bearings carried 40 by the framework and is rotated from the feeder (not shown) and operates through the groove 40, and roller 39 to reciprocate the bar 37, and the fingers carried thereby. The ends of the fingers 38 45 are flattened on each side and they serve to hold the seed cotton against the drum and also by their lateral movement, prevent the congestion of the cotton against the drum and blade and assist in the operation of stripping the lint from the seed. The freed seed drop through between the fingers 38, and fall onto the chute board 30, and pass thence to the conveyer 42, arranged under the gin and are carried by said 50 conveyer to any desired place. The strip- 55

per bar has considerable range of movement and clears the edge of the blade 12, when it has reached the limit of its upward movement and is withdrawn below the blade edge when pulled downward by the pull springs 18, and the rapid reciprocation thereof against the seed causes a continuous turning of the seed against the drum, thereby exposing all sides of the seed to the drum and blade, with the result that all the lint 60 is stripped from the seed and the congestion of the seed against the blade and drum is prevented. The suction through the perforations of the drum assisted by the fingers 38, holds the lint cotton, and the seed 65 closely against the drum until the lint is all stripped from the seed and the seed is then free to pass through the fingers 38, onto the chute board 30.

The support is a hollow member whose 70 ends are formed square in cross section and are held in correspondingly shaped openings 31, 31, in the ends of the framework, by means of the adjusting set screws 32, arranged as shown in Figure 3, and providing for the vertical and lateral adjustment thereof. The intermediate portion of the support is open underneath and the opposing side is arcuate in general contour and perforated and spaced from the drum, 75 and the admission of air therethrough is controlled by a suitable gate valve 35, which is manipulated through the valve grip 36. A wide chute 33 leads from the support 13, and enters the flue pipe 8, the front edge 80 of the lower wall of the chute being adjacent said support and the upper wall thereof being spaced from the drum and being also spaced from the semi-cylindrical hood 34, which closely fits around the upper part of 85 the drum. An inlet space is thus provided between the hood and chute for the admission of auxiliary air into said chute.

As before stated, a suction is created 90 through the flue pipe 8, causing a current 110 of air through the perforations of the exposed part of the drum and through the branch pipes 10, 10, and also through the perforations of the support 13, and the chute 33.

The cotton fed through the hopper 11 is held against the front part of the periphery of the drum 6, and is freed of the seeds by the combined action of the bar, the stripper blade, and the reciprocating fingers, as explained, and passes between the blade and drum into the chute 13. The admission of air through the perforations of the support counteracts the force of the suction through the branch pipes 10, 10, 120 and the current gradually separates the fiber, relieving it of motes and the like, and improving the staple and the current of auxiliary air entering the chute between the upper wall thereof and the drum relieves 125 130

the drum of the remaining lint adhering thereto which passes on out through the chute 33 to the flue pipe 8, by which it is delivered to the condenser. In case any of 5 the lint is drawn through the perforations of the drum into the interior thereof, this will also pass out at the ends of the drum through the branch pipes 10, 10, into the flue pipe 8 for delivery as before stated.

10 As the blade and stripper bar become worn requiring adjustment to hold them in proper relation to the drum and to each other, they may be adjusted through the instrumentalities provided for that purpose, 15 and hereinbefore described.

A number of gins of the class described may be arranged in alignment, forming a battery, and be readily accommodated by the same flue pipe 8, and the same hopper 20 11, and all thus arranged to feed the same condenser, resulting in economy of space and convenience in arrangement.

What I claim is:

1. In a cotton ginning mechanism, a perforated drum, a feed hopper arranged to deliver cotton at the upper part of the down moving side of the drum, means for drawing air inward through the drum, a knife blade adjacent the lower part of said down moving 30 side, a vertically moving stripper bar outside the knife, and a transverse series of fingers reciprocating transversely and having their ends near the upper limit of the path of the stripper bar, substantially as set 35 forth.

2. In a cotton ginning mechanism, the perforated drum, the hopper delivering to the down moving side of the drum, means for causing air to move inward through said 40 side, the series of transversely reciprocating fingers below the hopper and arranged to arrest the cotton and hold it against the drum, the knife below the fingers, and the stripper bar reciprocating vertically to and 45 from the line of the ends of the fingers.

3. In a cotton ginning mechanism, the perforated drum, the hopper delivering cotton to the down moving side of the drum, means for drawing air through the said 50 side, the tangentially arranged stationary knife with an upward directed operative edge, the vertically reciprocating stripper bar outside of the knife and arranged to push the seed upward, the transverse series 55 of fingers between the knife and the hopper and arranged to arrest the cotton and to move the seeds horizontally with reciprocating movements immediately above the edge of the stripper bar.

60 4. A machine for ginning cotton including a flue pipe, a hollow rotatable foraminated drum, branch pipes leading from the ends of the drum and entering said flue pipe, a hopper through which cotton is fed against 65 the periphery of the drum, a stripper blade,

whose edge is arranged adjacent the drum and against which the cotton is carried by the drum, said blade operating to strip the lint cotton from the seed therein, a reciprocating stripper bar arranged adjacent the 70 blade, and a chute arranged to receive the lint from said blade and to conduct the same from the drum to said flue pipe.

5. A machine for ginning cotton including a rotatable foraminated drum, a flue pipe 75 arranged behind said drum, branch pipes leading from the ends of the drum and entering said flue pipe, a chute whose inlet end is arranged beneath the drum and whose other end enters said flue pipe, a hopper 80 arranged to feed seed cotton onto the drum, a transverse blade between the hopper and chute, whose edge is arranged adjacent the drum, and a reciprocating stripper bar adjacent said blade and provided to operate 85 against the cotton held against said blade by the drum.

6. A machine for ginning cotton including a hollow, rotatable foraminated drum, a flue pipe arranged behind the drum, branch 90 pipes leading from the ends of the drum and entering said flue pipe, a chute, one end of which enters said flue pipe and the other end of which is arranged adjacent said drum, said last mentioned end being provided with 95 auxiliary air inlets, a hood embracing the upper side of the drum, a hopper provided to discharge seed cotton against the exposed portion of the drum, a stripper blade between the hopper and chute, whose edge is 100 adjacent the drum, the suction through the flue pipe creating a current through said chute and branch pipes and through the perforations of the exposed portion of the drum.

7. A machine for ginning cotton, including a hollow, rotatable, foraminated drum, a hood partially enclosing said drum, a stripper blade whose edge is arranged adjacent the drum, a hopper arranged to discharge seed cotton against the exposed portion of the drum, a flue pipe, a branch pipe connecting the interior of the drum with said flue pipe and through which an air current is induced from the suction through 115 the flue pipe, causing the intake of air into the drum through the perforations of the exposed portion thereof and holding the cotton to the drum, whereby it is carried into contact with said blade, a reciprocating 120 stripper bar adjacent the blade and operating against the cotton to prevent the congestion thereof adjacent the edge of the blade, and a chute arranged behind the blade and arranged to receive the lint cotton from 125 the drum, the inlet end of the chute being arranged adjacent the drum behind the blade and the other end thereof connecting with the flue pipe.

8. A machine for ginning cotton including 130

a hollow, rotatable, foraminated drum, a hood partially surrounding and enclosing the upper part of the drum but exposing said drum in front, a hopper arranged to deliver 5 seed cotton to the exposed portion of the drum, a flue pipe arranged behind the drum with which the interior of said drum communicates, the suction through said pipe inducing the intake of air through the perforations of the exposed part of the drum, causing said cotton to adhere to the drum, a transverse stripper blade, whose edge is arranged adjacent the drum underneath the hopper and against which the cotton is 10 carried by the drum, a reciprocating stripper bar arranged adjacent the blade and operating against the cotton held against the blade by successive strokes to prevent the congestion thereof against the blade, a chute 15 whose inlet end is arranged adjacent the drum and whose other end discharges into the flue pipe, the under wall of the inlet end of the flue having air inlets and the upper wall of said inlet end being spaced from 20 said hood.

9. A machine for ginning cotton including a hollow, rotatable, foraminated drum, a hood partially surrounding and enclosing the upper part of the drum but exposing said 30 drum in front, a hopper arranged to deliver seed cotton to the exposed portion of the drum, a flue pipe arranged behind the drum with which the interior of said drum communicates, the suction through said pipe inducing the intake of air through the perforations of the exposed part of the drum, causing said cotton to adhere to the drum, a transverse stripper blade, whose edge is arranged adjacent the drum underneath the 35 hopper and against which the cotton is carried by the drum, a reciprocating stripper bar arranged adjacent the blade and operating against the cotton held against the blade by successive strokes to prevent the congestion 40 thereof against the blade, a chute whose inlet end is arranged adjacent the drum and whose other end discharges into the flue pipe, the under wall of the inlet end of the flue having air inlets and the upper wall of said 45 inlet end being spaced from said hood, and means for controlling the passage of air through said air inlets.

10. A machine for ginning cotton, including a hollow, rotatable foraminated drum, 50 a hood partially enclosing the same, a hopper through which seed cotton is fed onto the exposed portion of the drum, a stripper

blade whose edge is arranged adjacent the drum, means inducing the inlet of air through the openings of the exposed portion 60 of the drum, said air operating to hold said cotton against the drum whereby it is carried between the blade and drum, said blade arresting the seed while the rotating drum strips the lint therefrom, a reciprocating stripper bar adjacent the blade and provided to agitate the cotton adjacent the blade edge to assist in stripping the lint from the seed and prevent the congestion of the cotton against said blade, and a chute one 65 end of which is arranged adjacent said drum, and disposed to receive the lint delivered from the blade by the drum.

11. In a cotton ginning mechanism, a rotary apertured drum, means for causing 75 air to pass inward through the down moving side of the drum, a transversely arranged knife blade having an upward directed edge arranged adjacent to but spaced from the periphery of the drum, a feed mechanism arranged to supply cotton to the upper part of said side of the drum, and means arranged to engage with the cotton on lines between the hopper and the knife, after the air has begun to act on the fiber at the periphery, to reciprocate the seeds horizontally and reciprocate them vertically to cause the rotation of the seed in the cotton and expose all sides thereof to the air suction, and separate them from the fiber. 80

12. In a cotton ginning mechanism, a rotary apertured drum, means for causing air to move inward through the wall of the drum, a transversely arranged knife blade having an upward directed edge arranged 85 adjacent the periphery of the drum, means for supplying cotton to the drum at points above the knife blade, a horizontally reciprocating bar arranged in front of the cotton-receiving part of the periphery of the 90 drum, and spaced fingers carried by said bar and inclined toward said drum to arrest the cotton and hold it against the drum and blade, said fingers operating to reciprocate the cotton after the air has commenced 95 to draw the lint against the drum and to distribute the seed along the blade.

In testimony whereof, he has signed his name to this specification in the presence of two subscribing witnesses.

JAMES C. GARNER.
